H. F. BECHMAN

STEREOTYPE PLATE CASTING BOX

Original Filed Oct. 10, 1922

Inventor

Henry F. Bechman Inventor
By Alexander Sowell Attorney!

UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-PLATE CASTING BOX.

Application filed October 10, 1922, Serial No. 593,567. Renewed June 19, 1925.

To all whom it may concern:

Be it known that I, HENRY F. BECHMAN, a citizen of the United States, residing at Battle Creek, in the county of Calhoun and 5 State of Michigan, have invented certain new and useful Improvements in Stereotype-Plate Casting Boxes; and I hereby declare that the following is a full, clear, and exact description thereof, reference being had to the accompanying drawings, which form part of this specification.

This invention is an improvement in stereotype plate casting boxes of the type shown in my Patent #853,752, of March 15 14th, 1907.

The objects of the present invention are to insure plates of uniform thickness; to automatically spread the matrix in the mold previous to the casting operation; to improve 20 the form of the cope so that the inflowing metal itself will also tend to spread the matrix in the mold; and to do away with the necessity of using any tail piece or pouring sheet to direct the metal into the mold.

The present invention embodies novel improvements in the construction of the cope, the drag, and the matrix positioning devices, as illustrated in the accompanying 30 drawings and hereinafter described; and the novel features of construction and novel combinations of parts for which protection is desired are set forth in the claims following the description.

In said drawings:

Fig. 1 is a top plan view of the upper part of the cope and drag of a casting box, closed ready for pouring.

Fig. 2 is a part vertical sectional view on the line 2-2 Fig. 1, showing the matrix in place.

Fig. 3 is a part vertical sectional view on the line 3-3 Fig. 1.

Fig. 4 is an enlarged detail section on the line 4-4 Fig. 3.

The cope and drag of the casting box may be constructed and arranged to operate substantially as described in my aforesaid patent, but improved as hereinafter pointed out, and therefore it is unnecessary to illustrate the entire casting box in the drawings. Only the upper portions of the cope and drag are shown, as these will suffice, in connection with the following explanation thereof, to

impart a full understanding of the invention.

As shown the drag 2 is constructed substantially as in my said patent with the exception that its upper portion is slightly contracted in internal diameter, as shown in Figs. 2 and 3, about one eighth inch, just above the upper edge of the matrix when in position in the drag, thereby forming an overhanging shoulder or ledge 2^a which will prevent the inflowing metal striking on the upper edge of the matrix and entering between the back of the matrix and the walls of the drag; and from forcing the facing sheet from the matrix, in case such sheet is used therewith.

On the upper end and front of the drag 2 is an extension or flange 2^b to direct the molten metal into the mould and prevent splashing thereof. This flange does away with the loose tail piece (or pouring sheet) which is ordinarily used for this purpose.

As shown, the cope 1 is constructed substantially as described in my aforesaid patent, but its upper portion 1^b (which projects above the matrix M when the box is closed, see Fig. 2) is slightly contracted in internal diameter forming an outwardly flaring shoulder or ledge 1^a at the lower end of part 1^b, said shoulder approximately coinciding with and lying opposite the shoulder 2^a of the drag when the box is closed. As the molten metal descends the space between the cope and drag it strikes the shoulder 1^a and is deflected thereby against the inside surface of the matrix M and forces the latter outwardly and closely against the inner wall of the drag below the shoulder 2^a. The contracted portion 1^b of the cope provides for a greater thickness of the casting at its upper or waste end above the matrix which thickened portion forms the "head" or "sprue" of the cast plate, which head is removed during the finishing operations on the plate.

The upper end of the part 1^b of the cope 1 is also beveled as shown at 1^c, adjacent the flanges 2^b when the box is closed. The space between the tapered portion 1^c and the flange 2^b forms a mouth into which the molten stereotype metal can be easily poured to fill the mold in casting a plate.

The matrix M may be of any suitable kind, and is placed in the drag 2 below the shoulder 2^a, and may be confined between

the cope and drag as explained in my aforesaid patent. Preferably the opposite vertical edges of the matrix M are engaged by clamp bars 5 hingedly attached to the opposite sides of the cope, as shown.

Clamp bars 5 are used to lock the matrix in place and also insure a uniformity of space between the cope and drag. Each clamping bar 5 is approximately L-shaped 10 in cross section and is hingedly connected to the adjacent side wall of the drag as shown, and has a vertical rib 5^a at its inner end the lower portion of which rib corresponds to the plate in thickness; and the upper portion 15 of such rib is adapted to fit over the shoulder 1^a and between and against the inner wall of the drag and the opposed portion 1^b of the cope, as indicated in Fig. 4. The side edges of the matrix M are adapted 20 to be placed against the bars 5 exterior to the ribs 5^a and are clamped between the end walls on the drag 2 and the rib 5^a, when the drag is closed; as shown in Figs. 1 and 4.

To spread the matrix in the mold so that 25 it will lie closely against the interior surface of the drag, flat springs 7 are fastened by screws 7^a to opposite sides of the exterior end walls of the drag and project in and through slots 2^b in the said end walls of the 30 drag just below the shoulder 2^a and coinciding with bars 5. The inner ends of the springs 7 project slightly beyond the inner wall of the drag and enter corresponding recesses 5^c in ribs 5^a as shown in Fig. 4. These 35 springs 7 are adapted to engage the opposite edges of the matrix M, as the latter is enclosed in the mold, and they tend to press these edges toward each other thereby causing the matrix to fit closely against the inner 40 wall of the drag below the shoulders 1^a, 2^a, just before the side edges of the matrix are clamped between the drag and the locking ribs 5^a.

When ready to cast a plate the drag 2 is 45 lowered and a matrix M is placed therein with its opposite edges entered into the drag and against the springs 7, the bottom end of the matrix M being held by the usual half ring (or so-called bull-ring—not shown). The 50 springs 7 engage the sides of the matrix near the upper end on both sides and hold same until the matrix side clamps 5 are closed on them. Then the drag is closed against the cope and the matrix M is automatically positioned in the mold beneath the shoulders 1^a, 2^a and around the lower cylindrical portion of the cope; the springs 7 spread the upper end of the matrix closely 55 beneath the shoulders 1^a, 2^a, and the opposite edges of the matrix are clamped between the ribs 5^a of locking bars 5 and the edges of the inner wall of the drag, whereby it is held securely in position.

The molten metal is poured into the box 65 mouth (between the beveled portion 1^c on

the upper end of the cope and the flange 2^b on the drag) and the inflowing molten metal descends around the part 1^b of the cope until it strikes the shoulder 1^a, whereby it is deflected outwardly against the upper end of 70 the matrix M, forcing the same closely against the inner walls of the drag; the metal fills the space below the shoulders 1^a and 2^a, and between the matrix M and the core, thus forming the plate proper. The 75 pouring is usually continued until the mouth is filled, the metal above the lower edge of the shoulder 1^a forming a sprue or head which is cut off the plate; by suitable mechanism, after the plate and head are removed 80 from the box.

What I claim is:

1. In a stereotype casting box; a drag; and a cope having its upper portion reduced in diameter below the pouring mouth and above the plate forming portion, substantially as described.

2. In a stereotype casting box; a cope; and a drag slightly contracted in internal diameter beyond the matrix holding portion, 90 to prevent the metal entering between the back of the matrix and the wall of the drag, substantially as specified.

3. In a stereotype casting box; a drag; and a cope, adapted to enclose a matrix; 95 and spring means adapted to engage the opposed edges of the matrix and position the same, substantially as described.

4. In a stereotype casting box; a drag; and a cope; the drag being slightly contracted in internal diameter beyond the matrix holding portions to prevent metal entering between the back of the matrix and the wall of the drag, and the cope having its upper end reduced in diameter above the 100 matrix.

5. A stereotype casting box comprising a drag and a cope adapted to enclose a matrix, means for clamping the matrix, and spring means adapted to engage the opposed edges of the matrix and position it in the box 110 when the same is closed.

6. A stereotype casting box comprising a drag, and a cope, adapted to enclose a matrix, and spring plates projecting through slots in the drag adapted to engage the opposed edges of the matrix and position the same in the box when the same is closed.

7. A stereotype casting box comprising a drag and a cope adapted to enclose a matrix, bars for clamping the matrix, and spring plates projecting through slots in the drag adapted to engage the opposed edges of the matrix and position it in the box when the same is closed.

8. A stereotype casting box comprising a drag and a cope adapted to enclose the matrix, spring means adapted to engage the opposed edges of the matrix and position it in the box when the same is closed, and clamp- 130

ing bars hinged to the drag adapted to clamp the edges of the matrix when the box is closed.

9. A stereotype casting box comprising a drag, and a cope, the drag being slightly contracted in internal diameter above the matrix holding portions, and the cope having its upper end reduced in diameter opposite the contracted portions of the drag

and cope, and matrix locking bars hinged to the drag, substantially as described.

10. In a stereotype casting box as set forth in claim 9, springs adapted to engage the opposed edges of the matrix and position it in the drag, substantially as described. 15

In testimony that I claim the foregoing as my own, I affix my signature.

HENRY F. BECHMAN.
